UNITED STATES PATENT OFFICE.

OLIVER L. DOSCH AND ALBERT A. ACKERMAN, JR., OF ELIZABETH, NEW JERSEY,
ASSIGNORS TO THE SINGER MANUFACTURING COMPANY, A CORPORATION OF
NEW JERSEY.

POWER-TRANSMITTER.

1,250,438.

Specification of Letters Patent.

Patented Dec. 18, 1917.

Application filed November 30, 1915. Serial No. 64,248.

To all whom it may concern:

Be it known that we, OLIVER L. DOSCH and ALBERT A. ACKERMAN, Jr., citizens of the United States, residing at Elizabeth, in the county of Union and State of New Jersey, have invented certain new and useful Improvements in Power-Transmitters, of which the following is a specification, reference being had therein to the accompanying drawings.

This invention relates to an improvement in power transmitters designed more particularly for use in connection with power-tables sustaining a number of sewing machines or other light-running machines required to be driven independently from a common source of power such as may be derived from a driving shaft extending lengthwise of and beneath the top of the table, as represented, for instance, in the United States patent to Herbert Corral No. 1,147,377, of July 20, 1915. It has for its object to provide a simple, compact and efficient construction of such a transmitter which shall be inexpensive to manufacture and which shall readily adapt itself to the power-shaft with the exercise of a minimum of care and skill in its installation.

In its preferred form, the transmitter comprises a hanger which may be composed of a standard affording a vertically adjustable upper section of a leg of the power-table and suitably recessed to embrace the moving parts, this standard having secured thereto for adjustment both horizontally and vertically a segmental support having upon its inner edge circumferentially spaced seats in spherical arrangement to receive the correspondingly formed adjacent portion of a closed casing containing the clutch-members of the transmitter and secured thereon for universal adjustment by means of suitable bolts.

The transmitter casing is preferably constructed of general cylindrical form with axially separable parts formed respectively with interengaging internal and external screw-threads affording means of relative axial adjustment.

One of the parts of the hanger is formed with a bearing boss containing a rotary end-wise-movable bushing in which is journaled the tubular hub or sleeve of a friction-disk constituting one section of a driven clutch-member and apertured to receive peripher-

ally spaced stud-pins upon a friction-disk constituting another section of said clutch-member which is sustained by and is spaced from and is axially movable relatively to the first-named section. The other part of the transmitter-casing has a bearing in which is journaled a sleeve upon which is slidably mounted by a spline-and-groove connection a disk or wheel, constituting the driving clutch-member, which is disposed intermediate the component sections of the driven clutch-member in operative relation with which its opposite faces are respectively disposed.

The bearing bushing for the driven clutch-member, which constitutes a part of one of the transmitter-casing sections, receives the thrust of one of the driven clutch-member sections in a clutching action, the thrust of the other clutch-member section being sustained by the other relatively adjustable part of the casing, and between these thrust-receiving portions of the casing and the respective clutch-member sections are preferably interposed anti-friction bearing rings to reduce the frictional resistance of the movable members when in operative engagement.

The rotary bushing preferably has in its periphery an inclined cam-slot entered by a roller stud projecting inwardly from the surrounding bearing-boss, and such bushing has adjustably secured thereon a collar provided with a lateral arm connected with a treadle- or knee-lever rod by which such bushing is turned to perform slight endwise movements for forcing the adjacent driven clutch-member section toward the other section and thereby frictionally gripping the driving clutch-member between them.

The part of the transmitter-casing provided with the movable bushing preferably has a concentric stationary braking element against which the adjacent driven clutch-member section may be forcibly drawn in the retraction of the bushing to disengage the clutching elements, the bushing preferably being at its outer end in abutting relation with the hub of a belt-wheel fixed upon the driven clutch-member sleeve for communicating power transmitted through the clutch to the machine to be driven.

The supporting sleeve for the driving clutch-disk is entered by the power-shaft which is secured therein by a set-screw or

other suitable means. In case the transmitter is used singly or is at the end of a series of such transmitters, the driving shaft need extend only partly through the sleeve 5 in which it is secured; but the transmitter may be applied to the shaft in any part of its length, in which case the shaft passes through both the sleeve of the driving clutch-member and the hub or sleeve of the 10 driven clutch-member. In either case the transmitter is entirely self-contained and sustains not only the weight of its moving parts but the axial thrust thereof in the driving and braking actions, so that the sole 15 function of the driving shaft is to communicate rotary movement to the driving clutch-member.

According to the present construction, as thus described, the clutching parts of the 20 transmitter are entirely housed within the casing for exclusion of foreign matter which would impair their efficiency and durability, while they are effectively shielded from the operator. The belt-wheel for communicating power to the machine to be driven is 25 preferably inclosed within a dress-guard removably attached to the casing-support and is provided with a socket in which may be secured a tube affording a housing for 30 the rotary driving shaft, the bearing boss at the opposite end of the transmitter-casing being provided with a collar having a similar socket to receive an oppositely extending housing tube for the driving shaft.

35 In the drawings, Figure 1 is a sectional side elevation of the upper portion of the leg of a power table sustaining a power transmitter embodying the present improvements. Fig. 2 is an end elevation of the 40 same, omitting the dress-guard and the pulley belted to the machine to be driven. Fig. 3 is an end elevation of the transmitter with the casing in section and certain of the contained parts omitted. Fig. 4 is a detail view 45 of the movable bearing bushing and the stud entering its cam-groove. Fig. 5 is an elevation, upon a smaller scale, of an entire leg of the power-table sustaining the power transmitter, and showing a portion of the 50 table-top in transverse section. Fig. 6 is a side elevation of the same with the table-top omitted, and Fig. 7 a plan of the parts represented in Fig. 6.

The transmitter-casing is shown constructed with a body section 1 of general cylindrical form with one end portion 2 reduced and rounded into substantially spherical form and the other end formed with an axial aperture of approximately its full diameter which is internally screw-threaded to receive the externally screw-threaded cap-section 3, forming therewith a substantially closed cavity to afford a housing for the clutching parts of the transmitter.

60 The cap-section 3 is provided with a tu-

bular boss 4 within which is fitted the tubular sleeve or arbor 5 having at its outer end the collar 6 and in its inner end portion the longitudinal groove or key-way 7. Within the groove 7 is fitted the spline 8 which is 70 secured within a groove of the inner periphery of the hub 9 of the driving disk or wheel 10 slidably mounted upon said sleeve, the spline being provided with a projecting pin 11 entering a radial aperture of the hub 9 75 to lock it in position within the latter. The driving disk 10 is provided with annular recesses in its opposite faces to receive the laterally projecting friction-rings 12 of soft material such as leather.

80 Within the bearing boss 13 of the transmitter-casing section 1 is fitted the rotary and endwise-movable bushing 14 which is provided in its periphery with the inclined cam-slot 15 entering by the roller 16 upon the stud 17 projecting inwardly from the bearing boss. Oscillatory movements of the bushing 14 cause the bushing to perform slight endwise movements within its bearing boss 13.

85 Journaled within the bushing 14 is the tubular hub or sleeve 18 of the clutch-disk 19 constituting one of the component sections of the driven clutch-member, the other section consisting of the clutch-disk 20 which is 90 formed with peripherally spaced lugs 21 having threaded apertures into which are tapped the similarly threaded ends 22 of the stud-pins 23 entering the similarly disposed tubular bosses 24 of the disk 19 by means of 100 which the disk 20 is sustained for rotation with but axial movement relative to the disk 19. The component sections of the driven member are axially spaced to embrace the driving disk 10, and are normally forced 105 apart out of driving engagement with the friction-rings 12 by means of the springs 25 interposed between the lugs 21 and the bosses 24.

110 The inner face of the cap 3 is adapted to receive the thrust of the hub of the friction-disk 20 in a clutching action, and between these parts is preferably introduced a thrust-bearing of well-known form, comprising a ring 26 having circularly spaced sockets containing the anti-friction balls 27 projecting slightly beyond the opposite faces of said ring and preferably resting in contact with the wearing rings 28 and 29 disposed upon opposite sides of the ring 26. Between the 115 hub of the friction-disk 19 and the adjacent end of the bushing 14 is preferably introduced a similar thrust-bearing comprising the ring 30 containing the circularly spaced anti-friction balls 31 adapted to contact with the wearing rings 32 and 33 on opposite sides thereof, the latter being shown set in a suitable recess in the end of the bushing.

120 The closed end of the transmitter-casing section 1 is shown formed with an inwardly 125

extending annular flange 34 recessed in its inner face to receive the soft friction-ring 35 which is opposed to the adjacent face of the disk 19 and normally engages the same to 5 serve as a brake for the driven clutch-member when the latter is disengaged from the driving clutch-member. The sleeve 18 is shown formed near its outer end with an annular groove 18' within which is fitted the 10 hub 36 of a split belt-wheel 37 which is peripherally grooved to receive the belt 38 connecting such pulley with the machine to be driven, the separable parts of the belt-wheel being secured together by means of the 15 bolts 39 passing through suitable lugs of the hub 36. By the means described, the bushing 14 is locked between the clutch-disk 19 and the hub of the belt-wheel, so that its endwise movements are communicated to said parts.

20 The power-shaft 40 which in practice usually extends throughout the length of the power-table, passes through the sleeves 5 and 18 of the driving and driven clutch-members and is secured within the former by means 25 of the set-screws 41 passing through the collar 6 and preferably engaging flattened portions of the shaft 40.

The bearing boss 13 of the transmitter-casing section 1 is shown provided with an 30 annular cavity 42 having a lateral opening 43. Secured upon the bushing 14 within this cavity is the split collar 44 clamped in position upon the bushing by means of the screw 45 and formed with a lateral arm 46 extending 35 through the opening 43 and provided at its outer end with an aperture entered by the treadle- or knee-lever rod 47 which is preferably formed with a head 48 intermediate which and the arm 46 is interposed the buffer-spring 49, a thrust-collar 50 being secured upon the rod 47 by means of the set-screw 51 to confine the parts together. The 40 operating rod 47 may be normally thrust upwardly by means of the usual spring to turn the bushing 14 into normal retracted position 45 in which the clutch-disk 19 is withdrawn from engagement with the driving disk 10 and is pressed against the brake element 35 to maintain the belt-wheel 37 stationary. When the operator moves the treadle- or knee-lever to draw the rod 47 downwardly, a regulated yielding pressure is imposed upon the arm 46 through the buffer-spring 49 to move the bushing 14 toward the 50 driving disk 10, thereby forcing the disk 19 in opposition to the springs 25 into engagement with the driving disk 10, and shifting the latter in turn into engagement with the disk 20, as represented in Fig. 1, whereby 55 the axially movable driving member is gripped between the axially separable sections of the driven member, and driving relation between them is established.

It is evident that the degree of pressure 60 between the clutching elements of the trans-

mitter is under complete control by the operator, so that any speed of the driven member may be readily attained up to a maximum determined by the speed of the driving shaft 40. It is further evident that in the 70 reverse movement of the rod 47 to stop the machine, not only may the clutch-members be forcibly shifted, but the retractive force may be determined by the operator, so as to produce any desired degree of pressure between the driven member and the braking element to effect either a gradual or abrupt stoppage of the machine to be driven.

75 As the friction elements become worn, the separable sections of the casing may be adjusted by turning the cap-section 3 to vary the distance apart of the respective end-thrust resisting walls, the end cap being secured in its position of adjustment by means of the set-screw 52 introduced within a 80 threaded aperture of the casing section 1 and bearing upon a soft-metal plug 53 resting upon the threaded periphery of the cap.

85 The ends of the two sections of the transmitter-casing are preferably formed with 90 outwardly flaring annular oil cavities 54 and 55 entered by the similarly formed flanges 56 and 57 upon the hubs of the disks 19 and 20 to insure that oil from the bearings may not reach the friction-rings 12 and 35. The 95 bushing 14 is shown provided with a lubricant-cavity 58 connected with its inner face by means of the oil-holes 59, such cavity being in practice filled with cotton waste or other medium saturated with oil; and this 100 bushing is formed near its outer end with an annular cavity 60 surrounding an annular groove 18'' of the sleeve 18 and connected with the oil-cavity 54 by means of the downwardly inclined duct 61 for insuring 105 against the escape of oil from the bushing.

110 The bearing boss 4 is similarly provided with an annular lubricant-cavity 4' connected with its bearing face by means of distributing apertures 4''. The boss 4 has preferably secured thereon a collar 62 having in its upper face the lubricant-cavity 63 containing a suitable packing saturated with oil, and communicating with the cavity 4' by means of an aperture 64. 115 The collar 62 is split at its outer end and provided with the apertured lug 65 entered by the clamp-screw 66 to clamp the apertured end of such collar upon the split housing tube 67 extending to the adjacent transmitter or to the end of the table for shielding the operator from the driving shaft.

120 The spherical exterior 2 of the body section of the transmitter-casing rests upon the similarly formed faces of the circularly 125 spaced bearing seats 68 of a segmental supporting plate 69 formed with apertures 70 adjacent said seats to receive the shanks of screw-bolts 71 tapped into correspondingly spaced lateral lugs 1' of the casing section 130

- 1, conical-faced washers 72 being preferably interposed between the heads of the stud-bolts and correspondingly shaped countersinks at the outer ends of the apertures 70.
- 5 Sufficient clearance is provided between the stud-bolts 71 and the walls of the apertures 70 to permit slight lateral play of the latter in relatively adjusting the lugs 1' toward and from the support 69 to produce a slight 10 universal angular adjustment of the casing and the movable parts contained therein.
- The supporting plate 69 is shown provided with lateral lugs 73 having in their upper edges notches or recesses 74 entered by 15 clamp-bolts 75 which pass through suitable flanges 76 of the dress-guard 77 open at the top and incasing the pulley-wheel 37 to shield the operator from the belt-wheel 37 and belt 38, which are omitted from Fig. 5.
- 20 to expose the parts behind the same. The guard 77 may be readily removed by merely loosening the nuts of the bolt 75 so that in lifting the guard from operative position the bolts may be raised out of the notches 74.
- 25 The guard 77 is shown provided with a split bearing boss 78 in which is clamped one end of a split housing tube 67' serving at the opposite end of the transmitter a purpose similar to the tube 67 in inclosing the driving shaft 40.
- The lugs 73 of the supporting plate 69 are formed with elongated vertically extending apertures 79 entered by clamp-bolts 80 having their heads 81 suitably countersunk and 30 passing through transverse elongated apertures 82 formed in the laterally spaced members 83 of a standard 84 constituting the upper section of a table-leg comprising the straight lower section 85.
- 35 The section 85 is formed near its upper end with a slot 86 entered by the clamp-bolt 87 passing through a similar slot 88 of the section 84 for securing the parts together for relative vertical adjustment. Tapped 40 into a suitable boss 89 at the bottom of the standard 84 is the adjusting bolt 90 whose head rests upon the lateral lug 91 of the leg-section 85, the two parts of the leg being relatively adjustable vertically by means of the 45 bolt 90 to which is applied the jam-nut 92.
- The members 83 of the standard 84 are formed with seats 93 at the tops and with the divergently projecting extensions 94 and 95 respectively, each formed at its upper 50 extremity with the seat 96. Secured upon the extension 95 is a strip 97 upon which and the seat of the opposite extension 94 rests a table-top section formed of the separate parts 98, 99 and 100. The parts 98 and 60 100 have secured thereto the depending rails 101 which are laterally notched to receive the lateral tongues 99' of the part 99, (Fig. 5). The parts 98 and 100 are secured in position by means of a transverse cleat 102 and bolts 65 103 passing through the same and the rails

101, bolts 104 passing through the cleat 102 and the table-parts 99 serving to hold the latter against endwise displacement.

The power-table to which the present improvement is shown applied is of that type 70 comprising legs or standards spaced apart lengthwise of the table and connected together in pairs transversely thereof by means of suitable cross-braces, the table-top being formed of sections extending longitudinally above the component pairs of said legs or standards and each adapted to support one or more sewing machines with an intermediate work-supporting section; but a complete table is not shown herein, as the 75 table construction as a whole forms no part of the present improvement.

While the power-transmitter is herein shown and described in its preferred embodiment, it is evidently adapted for material modification of the construction and arrangement of its parts within the scope of the present invention.

Having thus set forth the nature of the invention, what I claim herein is:—

1. In a power transmitter, in combination, a hanger, driving and driven clutch-members journaled therein, one of said clutch-members being constructed with axially separable sections and the other being axially movable and disposed intermediate and in operative relation with the component sections of the first-named member, and means for effecting simultaneously the power-transmitting engagement of both of the separable clutch-member sections with the intermediate member.

2. In a power transmitter, in combination, a hanger, driving and driven clutch-members journaled upon independent normally stationary supports of said hanger, one of said clutch-members being constructed with axially separable sections and the other being axially movable and disposed intermediate and in operative relation with the component sections of the first-named member, and means for effecting simultaneously the power-transmitting engagement of both of the separable clutch-member sections with the intermediate member.

3. In a power transmitter, in combination, a hanger, a driven clutch-member journaled therein and constructed with axially separable sections of which one is movable toward and from the other, a driving clutch-member also journaled within and axially movable relatively to said hanger and disposed intermediate and in operative relation with the separable sections of the driven clutch-member, and means applied to the movable clutch-member section for forcing it into operative engagement with the driving clutch-member and the driving clutch-member into operative engagement with the other section of the driven clutch-member.

4. In a power transmitter, in combination, a hanger, driving and driven clutch-members journaled therein, one of said clutch-members being constructed with axially separable sections of which one is journaled in said hanger and itself affords a support for the other section, and the other clutch-member being also journaled within said hanger and disposed intermediate and in operative relation with the separable sections of the first-named clutch-member, a spring for maintaining the clutch-member sections normally separated, and manually operated means acting in opposition to said spring for imposing a variable and regulated pressure of the component sections of one clutch-member upon the other clutch-member intermediate the same. 70
5. In a power transmitter, in combination, a hanger comprising axially separable parts, driving and driven clutch-members each mounted upon a different one of said separable parts of the hanger, one of said clutch-members being constructed with axially separable sections and the other being axially movable and disposed intermediate and in operative relation with the component sections of the first-named member, and means for effecting simultaneously the power-transmitting engagement of both of the separable clutch-member sections with the intermediate member. 80
6. In a power transmitter, in combination, a hanger comprising axially separable parts forming between them a closed cavity, driving and driven clutch-members arranged within said cavity and each mounted upon a different one of said separable parts of the hanger, and means controlled from the exterior of said cavity for effecting the operative engagement of said clutch-members. 85
7. In a power transmitter, in combination, a hanger, driving and driven clutch-members journaled therein, one of said clutch-members being constructed with axially separable sections and the other being axially movable and disposed intermediate and in operative relation with the component sections of the first-named member, axially spaced thrust-bearings embracing between them and adapted for engagement with the component sections of the driven clutch-member, and means applied to one of said thrust-bearings for forcing together into driving relation said clutch-member sections and the intermediate clutch-member. 100
8. In a power transmitter, in combination, a hanger provided with a brake element, driving and driven clutch-members journaled in said hanger, one of said clutch-members being constructed with axially separable sections and the other being axially movable and disposed intermediate and in operative relation with the component sec- 105
- tions of the first-named member, and manually operated means for moving one of said clutch-member sections in one direction to establish driving relation of the driving and driven members and in the opposite direction to force it into operative relation with said brake element. 75
9. In a power transmitter, in combination, a hanger, driving and driven clutch-members journaled therein, one of said clutch-members being constructed with axially separable sections and the other being axially movable and disposed intermediate and in operative relation with the component sections of the first-named member, controlling means for effecting simultaneously the power transmitting engagement of both of the separable clutch-member sections with the intermediate member, means sustained by said hanger for receiving the thrust imposed upon the clutch-members by said controlling means, and a driving shaft operatively connected with said driving clutch-member and relative to which said clutch-member is adapted to perform axial movements. 85
10. In a power transmitter, in combination, a hanger, a driven clutch-member journaled therein and constructed with axially separable sections, a driving clutch-member disposed intermediate and in operative relation with the separable sections of the driven clutch-member, a sleeve journaled in said hanger independently of the driven member and affording a support for the driving clutch-member with which it is connected for rotation, and means for effecting simultaneously the power-transmitting engagement of the driving clutch-member with both sections of the driven clutch-member. 95
11. In a power transmitter, in combination, a hanger, a driven clutch-member journaled therein and constructed with axially separable sections, a driving clutch-member disposed intermediate and in operative relation with the separable sections of the driven clutch-member, a sleeve journaled in said hanger independently of the driven member and upon which the driving clutch-member is splined for axial movement thereon while turning with the same, a driving shaft entering and rigidly secured within said sleeve, and means for effecting simultaneously the power-transmitting engagement of the driving clutch-member with both sections of the driven clutch-member. 105
12. In a power transmitter, in combination, a hanger comprising axially adjustable and separable parts, driving and driven clutch-members journaled therein, one of said clutch-members being constructed with axially separable sections and the other being axially movable and disposed intermediate and in operative relation with the component sections of the first-named member, 110
13. In a power transmitter, in combination, a hanger comprising axially adjustable and separable parts, driving and driven clutch-members journaled therein, one of said clutch-members being constructed with axially separable sections and the other being axially movable and disposed intermediate and in operative relation with the component sections of the first-named member, 115
14. In a power transmitter, in combination, a hanger comprising axially adjustable and separable parts, driving and driven clutch-members journaled therein, one of said clutch-members being constructed with axially separable sections and the other being axially movable and disposed intermediate and in operative relation with the component sections of the first-named member, 120
15. In a power transmitter, in combination, a hanger comprising axially adjustable and separable parts, driving and driven clutch-members journaled therein, one of said clutch-members being constructed with axially separable sections and the other being axially movable and disposed intermediate and in operative relation with the component sections of the first-named member, 125
16. In a power transmitter, in combination, a hanger comprising axially adjustable and separable parts, driving and driven clutch-members journaled therein, one of said clutch-members being constructed with axially separable sections and the other being axially movable and disposed intermediate and in operative relation with the component sections of the first-named member, 130

axially spaced thrust-bearings embracing between them and adapted for engagement with the component sections of the first-named clutch-member, and means for effecting simultaneously the power-transmitting engagement of both of the separable clutch-member sections with the intermediate clutch-member.

13. In a power transmitter, in combination, a hanger comprising separable parts adjustably connected by inter-engaging internal and external screw-threads formed in or upon the respective parts, driving and driven clutch-members each mounted upon a different one of said separable parts of the hanger, one of said clutch-members being constructed with axially separable sections and the other being axially movable and disposed intermediate and in operative relation with the component sections of the first-named member, axially spaced thrust-bearings sustained by the respective separable parts of the hanger and embracing between them and adapted for engagement with the component sections of the first-named clutch-member, and means connected with one of said thrust-bearings for forcing said clutch-member sections into engagement with the intermediate clutch-member.
14. In a power transmitter, in combination, a hanger comprising a supporting member and a bearing member mounted thereon by a universal-joint connection, driving and driven clutch-members journaled within said bearing member, means for establishing and interrupting operative engagement between

the driving and driven clutch-members, and a shaft entering said bearing member and connected to one of said clutch-members which affords a support therefor.

15. In a power transmitter, in combination, a hanger comprising a supporting member provided with a substantially spherical seat, and a bearing member fitted externally to said seat with means for securing it adjustably thereon, driving and driven clutch-members journaled within said bearing member, means for establishing and interrupting operative engagement between the driving and driven clutch-members, and a shaft entering said bearing member and connected to one of said clutch-members which affords a support therefor.

16. In a power transmitter, in combination, a hanger comprising a standard, a supporting member with means for securing it adjustably, vertically and horizontally thereon, and a bearing member mounted upon said supporting member by a universal-joint connection, driving and driven clutch-members journaled within said bearing member, means for establishing and interrupting operative engagement between the driving and driven clutch-members, and a shaft entering said bearing member and connected to one of said clutch-members which affords a support therefor.

In testimony whereof, we have signed our names to this specification.

OLIVER L. DOSCH.
ALBERT A. ACKERMAN, JR.
